TIMING DEVICE

Irwin G. Boehm, Dayton, Ohio

Application December 26, 1939, Serial No. 310,900

7 Claims. (Cl. 89—1.5)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to a timing and switching device to be used in connection with bomb-releasing mechanism for controlling the interval of release of bombs.

The invention is particularly adapted for use in connection with a bomb-releasing mechanism in which bombs are released by repeated action of a solenoid. Such a bomb-releasing mechanism is illustrated in Patent No. 1,980,375, although it is to be understood that the device is adapted to be used with other types of electrical-energized bomb-releasing mechanism.

It is an object of this invention to provide a device for establishing the interval of release of bombs.

It is another object of this invention to provide a device for establishing the period of dwell between operations of electrically-energized bomb-releasing mechanism.

It is still another object of this invention to provide a device for establishing a selected period of dwell between operations of electrically-energized bomb-releasing mechanism.

In the drawings:

Fig. 1 is a side elevational view of one form of the device.

Fig. 2 is a cross-sectional plan view taken generally along the lines 2—2 of Fig. 1.

Fig. 3 is a cross-sectional view taken along the lines 3—3 of Fig. 2.

Fig. 4 is a cross-sectional view taken along the lines 4—4 of Fig. 3.

Fig. 5 is a cross-sectional view taken along the lines 5—5 of Fig. 3.

Fig. 6 is a detail plan view of a modified form of the device taken generally along the lines 6—6 of Fig. 7.

Fig. 7 is a cross-sectional view taken along the lines 7—7 of Fig. 6.

Fig. 8 is a detail plan view of the electrical connections as seen along the lines 8—8 of Fig. 7.

Referring to the drawings, and particularly to the embodiment of the invention illustrated in Figs. 1 through 5, the release-controlling mechanism is contained within casing 1 and comprises a constant-speed motor 2, the drive shaft of which has connected thereto a gear 3 meshing with gear 4 mounted on a squared portion of shaft 5. Fastened to shaft 5 to rotate therewith are a series of different-sized gears 7 through 17.

Freely rotatably mounted on shaft 5 are a series of brackets, all of which are numbered 29, since they are identical in construction except for slight differences in size. Each bracket 29 carries a gear in meshing engagement with one of the gears 7 through 17. The bracket-carried gears are numbered 18 through 28 and are of various sizes. Shaft 40 has mounted thereon to rotate therewith a series of different-sized gears numbered 41 through 51. As shown in Figs. 3 and 4, each gear in the sequence 18 through 28 is in alignment with and adapted to mesh with a gear in the sequence 41 through 51 for the purpose of driving shaft 40 at a desired speed. Gears 18 through 28 are constantly urged into meshing engagement with their corresponding gears by springs 30, one of which is connected at one end to the lower end of each bracket 29 and at the other end to the casing. As shown in Fig. 3, gear 24 is held out of meshing engagement with its corresponding gear 47 by a tongue 31 on bracket 29 engaging cam 67. Cam 67 is provided with a recessed portion 78 for the tongue 31 to drop into, permitting rotation of bracket 29 and gear 24 under the action of spring 30 about shaft 5 into meshing engagement with gear 47. Each of the gear-carrying brackets 29 is provided with a similar tongue 31. Cam 67 is mounted on shaft 72 to rotate therewith along with cams 61 through 66 and 68 through 71, which cooperate with the brackets carrying gears 18 through 23 and 25 through 28. Cams 61 through 66 and 68 through 71 are each provided with a recess similar to recess 78, and for the same purpose. These recesses are arranged in staggered relation so that only one bracket-carried gear at a time will be brought into engagement with its corresponding gear on shaft 40, as shown in Figs. 4 and 5.

Integral with shaft 72 is a gear 80 which meshes with a gear 81 operable by knob 82 for controlling the rotational position of shaft 72 and, consequently, the selection of gears for transmitting rotational movement of shaft 6 to shaft 40.

Mounted on shaft 40 to rotate therewith is a cam member 83 formed of non-conducting material except for a metallic electrical contact disk 85 and a metal cam portion 84 electrically connected with the contact disk. Contact member 86, carried by insulating block 87, sweeps against disk 85 to establish electrical contact therewith. Slidably mounted in block 87 is a plunger member 89 pressed into engagement with metal cam portion 84 by electrical conducting spring 90. Member 89 is electrically connected by spring 90 and conductor 91 to lead wire 92. Lead wires

88 and 92 extend to connections 93 and 94 to enable the device to be connected in circuit with a source of electrical energy and a solenoid-operated bomb-releasing mechanism such as described in Patent 1,980,375. Contacts 95 and 96 are for the purpose of connecting motor 2 to a source of electrical energy.

Dial 190, suitably attached to knob 82, has indicia thereon representing bomb spacing in feet, alignable with indicia on the casing representing ground speed in miles per hour. Setting dial 82 at a selected bomb-dropping interval brings into mesh a combination of gears for rotating shaft 72 and the make-and-break contactor at a speed which releases the bombs at the desired spacing.

The operation of the embodiment of the invention described above is as follows:

Constant-speed motor 2 is put into operation by operating a suitable switch (not shown) in the circuit which connects the motor to a source of electrical energy. Knob 82 is rotated to the desired bomb-spacing for the speed of the plane, the tongue 31 of bracket 29, carrying the gear for producing the desired interval of bomb release, being urged into the notch of one of the cam or notched disk members carried on shaft 72. Shaft 40, rotor 83, make-and-break contactor 86, 89, and the bomb-releasing solenoid connected therewith are operated at a rate to release the bombs at the predetermined interval.

Referring to the second embodiment of the invention, as illustrated in Figs. 6, 7, and 8, a housing 101 contains a constant-speed motor 102 drivingly connected by gears 103 and 104 to shaft 105 having gears 106 through 109 fixed thereto. Gear 106 meshes with gear 112 freely rotatably mounted on shaft 111. Fastened to gear 112 to rotate therewith is a cam member 110. Similarly, gear 107 meshes with gear 113 having cam member 114 integral therewith; gear 108 meshes with gear 116 having cam member 115 integral therewith; and gear 109 meshes with gear 117 having cam member 118 integral therewith. Each gear and cam combination is freely rotatably mounted on shaft 111 and is held in spaced relation by spacer sleeves, as shown in Fig. 6.

Associated with each cam is a make-and-break contactor or switch. The switch shown in side elevation in Fig. 7 will be described in detail, it being understood that the other three switches are identical in construction.

Referring to Fig. 7, fixed contact 122 is mounted on a block 119. Movable contact member 126 is mounted on a block 128 and is adapted to be moved into contact with member 122 by cam 115. Contact member 126 springs out of engagement with contact 122 when the portion 129 thereof drops into cut-out portion 130 of the cam. It is to be understood that cams 110, 114, and 118 are also provided with cut-out portions. Similarly, contacts 124, 125, and 127, as shown in Fig. 8, are movable into engagement with contacts 120, 121, and 123, respectively, by cams 110, 114, and 118. Contacts 124 through 127 are electrically connected by leads 130 through 133 to switches 134 through 137, respectively. Switches 134 through 137 are electrically connected to a solenoid operating a bomb rack of the type as shown in Patent 1,980,375.

The operation of the second embodiment of the invention is as follows:

The constant-speed motor drives shaft 105 which, through the medium of the gears, drives the contact-operating cams at different rates of

speed. The switch selected for the release interval or bomb-spacing desired is turned on and the remaining switches turned off.

It is to be understood that various modifications may be made in the device without departing from the spirit of the invention, it being intended to be limited only by the appended claims.

I claim:

1. A device for establishing the interval of release of bomb-dropping mechanism adapted to release a bomb upon each energization of electrical means, comprising a make-and-break contactor, means for operating said make-and-break contactor, constant-speed driving means, a shaft operatively connected to said driving means to be rotated thereby, a plurality of varied-sized gears carried by said shaft, a plurality of brackets freely rotatably carried by said shaft, a gear rotatably carried by each bracket in meshing engagement with one of said shaft-carried gears, a shaft rotatably carrying said make-and-break-contactor-operating means, a plurality of varied-sized gears carried by said last-named shaft, and means for selectively moving said brackets to bring a bracket-carried gear into mesh with a gear carried by said last-named shaft.

2. A device as recited in claim 1, in which said selective moving means comprises means constantly urging said brackets into gear-meshing position, a tongue on each bracket, and a disk operatively associated with each tongue for holding said brackets out of gear-meshing position, each of said disks having a notch in the periphery thereof for the reception of one of said tongues to permit movement of one of said brackets into gear-meshing position, said notches and tongues being staggered so that only one tongue is received in its corresponding recess at one time.

3. In combination, constant-speed driving means; a shaft operatively connected to said driving means; gear means connected to said shaft to rotate therewith; a plurality of brackets freely rotatably mounted on said shaft; a gear rotatably carried by each bracket, said bracket-carried gears being of different sizes; a make-and-break contactor mechanism; a cam for actuating the same; a rotatably-mounted cam shaft with which said cam is integral; gear means integral with said cam shaft; and means for moving a selected bracket-carried gear into operative engagement with said gear means.

4. In combination, a constant speed driving means and a shaft driven thereby, a plurality of variable-sized gears integral with said shaft to rotate therewith, a plurality of brackets freely rotatably mounted on said shaft, a gear carried by each of said brackets in mesh with one of said bracket-carried gears, said bracket-carried gears being of different sizes, a make-and-break contactor mechanism, a cam for actuating the same, a rotatably mounted cam shaft with which said cam is integral, a gear means integral with said cam shaft, and means for moving a selected bracket-carried gear into operative engagement with said gear means.

5. In combination, a constant speed driving means and a shaft driven thereby, a plurality of variable-sized gears integral with said shaft to rotate therewith, a plurality of brackets freely rotatably mounted on said shaft, a gear carried by each of said brackets in mesh with one of said bracket-carried gears, said bracket-carried gears being of different sizes, a make-and-break contactor mechanism including a rotatable member and gear means integral therewith, and means

for moving a selected bracket-carried gear into operative engagement with said gear means.

6. In combination, a constant speed driving means and a shaft driven thereby, a plurality of variable-sized gears integral with said shaft to rotate therewith, a plurality of brackets freely rotatably mounted on said shaft, a gear carried by each of said brackets in mesh with one of said bracket-carried gears, said bracket-carried gears being of different sizes, a make-and-break contactor mechanism including a rotatable member and gear means integral therewith, and means for bringing a particular bracket-carried gear into meshing engagement with said gear means including a rotatably mounted notched disk operatively associated with each of said brackets, each of said brackets having an integral projecting portion receivable in the notched portion of said disk when said bracket-carried gear and said gear means are in mesh.

7. A device for establishing interval of release, comprising a make-and-break contactor, driven means for operating said make-and-break contactor, constant-speed driving means, a plurality of variable-speed transmitting means operatively associated with said driving means, a bracket for carrying each of said transmitting means, and means for selectively moving one of said transmitting means into operative relationship with said driven contactor-operating means comprising a projection on each bracket and a notched disk operatively positioned with respect to each projection—the disks being movable into position for receiving their corresponding projections, and a shaft on which said disks are mounted with their projection-receiving openings in staggered relation.

IRWIN GEO. BOEHM.
